TYPEWRITER DESK

Filed July 8, 1927

UNITED STATES PATENT OFFICE

JENS VAALER, OF CHICAGO, ILLINOIS, ASSIGNOR TO THE CLEMETSEN COMPANY, OF CHICAGO, ILLINOIS, A CORPORATION OF ILLINOIS

TYPEWRITER DESK

Application filed July 8, 1927. Serial No. 204,154.

This invention relates to improvements in typewriter desks of the type in which the typewriter is swung into the desk when not in use and moves outwardly and upwardly for use, and more particularly to an improvement in the arrangement of the swinging door, which door closes the typewriter well when the typewriter is not in use.

One of the objects of my invention is to provide a means of preventing the swinging door from moving downwardly to such position that the knobs, handles, or ornamental projections that are located on the door would strike the base rail when the door is being pushed backwardly in a horizontal position into the well of the desk to be out of the way of the operator during the use of the typewriter. In the former construction of typewriter desks, the knobs, handles or ornamental projections would tend to strike the base rail were the least amount of downward pressure applied to the door when the door was pushed horizontally into the well of the desk. Thus there would be a tendency to break or mar the knobs, handles or ornamental projections, or interfere with the pushing of the door into the desk.

My invention further resides in the combination, construction and arrangement of parts shown in the accompanying drawing, and while I have shown therein a preferred embodiment, I wish it understood that the same is susceptible of modification and change without departing from the spirit of my invention.

Further objects, advantages and capabilities will later more fully appear and are inherently possessed by my invention.

Referring now to the drawing, in which is illustrated one embodiment of my invention:

Fig. 1 is fragmentary view in vertical cross section showing my invention applied to the swinging door of a typewriter desk, the door being shown in horizontal position preparatory to being pushed into the well of the desk;

Fig. 2 is a fragmentary view in elevation with a part in section, taken in the plane 2—2 of Fig. 1;

Fig. 3 is a fragmentary view in perspective of my invention.

Referring now in greater detail to the drawings, 1 is a typewriter desk of the type in which the typewriter is swung into the desk when not in use and moved outwardly and upwardly for use, and provided with a top 2, pedestals 3 and 4, and a base rail 5. A swinging door 6 is pivotally connected to the sliding carriage 7 by means of a hinge 8, the hinge being provided with a spring 9. The carriage is constructed with rollers or projections 10 which enter the slot 11 in the slides or runners 12. The spring tends to swing the door into vertical position so that when the typewriter is swung into the desk and the door is in its withdrawn horizontal position, the spring will tend to close and keep the door in vertical position. The door 6 is provided on its face with a series of knobs or handles 13.

A guide lug 14 is rigidly mounted on one side of the door. Generally a guide lug on but one side is sufficient, although the door may be provided on both sides with such lugs. This guide lug is preferably positioned on the inside or side adjacent the operator. The guide lug comprises a horizontal portion 15 having a downwardly extending lip 16 adapted to be driven into or embedded in the door, an upstanding portion 17, and an arcuate flange or extension 18. A screw 19 combined with the downwardly extending lip 16, holds the lug rigidly in place. This arcuate flange or extension is positioned so that it engages with the slot or groove 11 before the central knob or handle is in a position to contact with the base rail. There is no danger of the lower knob or handle striking or impinging against the base rail, for the reason that it is positioned in close proximity to the hinge member 8.

When the door is in horizontal position as shown in Fig. 1 of the drawings, the lug due to its arcuate contour guides itself into the slot or groove 11 on the slide or runner 12, thus insuring that the door will slide backwardly into position without striking the knobs or handles.

Having shown and described my invention, I claim:—

- 5 1. In a desk construction provided with a base rail and a well adapted to house a typewriter, runners in said well and provided with a longitudinal slot, a slideable carriage within said well and carried by said runners, a door provided with knobs or handles and being hinged to said carriage to
- 10 swing the door into a horizontal position and be pushed into the well of the desk, a guide lug connected to said door and having an extension adapted to be received by said slot for preventing said knobs or handles
- 15 from impinging against said base rail when the door is pushed into said well, said extension of said guide lug being arcuate shaped to facilitate the initial entrance of said extension into said slot.
- 20 2. A guide lug for a typewriter desk door, comprising a body part, a downwardly extending lip adapted to be driven into said door, an upstanding portion, and an arcuate flange extending laterally from said portion
- 25 adapted to be received by a slot in said desk for guiding said door.

In witness whereof, I hereunto subscribe my name to this specification.

JENS VAALER.
